LUBRICANT DISPENSER

Harry R. Tear, Evanston, Ill., assignor to The Lubrication Corporation, Chicago, Ill., a corporation of Delaware

Application March 3, 1937, Serial No. 128,723

30 Claims. (Cl. 221—47.3)

This invention relates to dispensing apparatus, and is illustrated as embodied in low-pressure "guns" for dispensing lubricating oil packaged in the original cans.

5 One object of the invention is to force the contents from the can while leaving the can body intact, so that there need be no drippage afterwards from the empty can if it is kept right side up. With this object in view, I arrange the apparatus so that one end of the can is first punctured to provide an outlet or discharge opening, and is then cut out and forced toward the bottom of the can to force the contents out through the discharge opening. This end of the can is 10 preferably faced with a packing member, such as a disk of cardboard, formed with a central opening which registers with the above-described discharge opening formed in the can end.

Another object of the invention is to provide 20 the apparatus with power for performing the cutting operations. In the embodiments selected for illustrations, a piston operated by compressed air is arranged to move the cutters and the can relatively to each other as described above, and preferably also operates the means for forcing the oil from the can.

An important feature of the invention, embodied in the preferred form herein described, has 30 to do with simplifying the construction of apparatus of this character, by supporting the cut-out can end against movement and forcing the can body upward over it.

The means shown for cutting out the can end, and supporting it while the oil is forced out of 35 the can, includes a plunger long enough to force the cut-out can end to the bottom of the can, and which is stationarily mounted if the air pressure moves the can body over the plunger, or is moved by the air pressure to actuate the cut-out 40 can end if the can body is stationarily supported.

This plunger has at its forward end a seal engaging the can end in a zone surrounding the discharge opening and is provided with a passage through which the oil is forced from said 45 opening to a suitable conduit designed for insertion into the filler opening of a transmission casing or differential housing or the like. The seal is preferably mounted yieldingly on the plunger, in a novel manner described below, so 50 that it is held firmly against the can end while it is being cut, and then shifts it forward ahead of the knives so that the can end can be forced clear to the bottom of the can although the knives do not travel quite that far and therefore 55 cannot possibly damage the can bottom.

The above and other objects and features of the invention, including a novel interlock preventing the opening of the air valve when the apparatus is opened up for the insertion of a new can, and other novel combinations and desirable arrangements of parts, will be apparent from the following description of the illustrative embodiments shown in the accompanying drawings, in which:

Figure 1 is a section longitudinally through one 10 embodiment of the invention, in which the can body is moved and the cut-out can end is stationary in dispensing the contents of the can;

Figure 2 is a section through the can or cartridge, showing the arrangement of the packing 15 member; and

Figures 3 and 4 are sections through other embodiments.

The package or container intended to be used with the illustrated apparatus is preferably a 20 can or cartridge having the end structure shown in Figure 2. This can includes a can body 10, formed in any usual manner, and having seamed thereto ends 12, either of which is intended to be cut out entirely free from the can body, and moved as a piston to the bottom of the can to 25 force out the contents. Each of these ends is shown faced with a packing member such as an annular cardboard disk 14 or the like arranged to leave a central unobstructed can-end portion 30 16 adapted to be pierced as described below, to 35 form an outlet or discharge opening.

The above-described container is claimed in my application No. 110,968, filed November 16, 1936.

Whether or not this exact form of container is 35 used, the can of oil is preferably arranged (as shown in dotted lines in Figure 1) in a two-part housing. One part 18 of the housing is long enough to receive the can and (in this particular embodiment) serves as a cylinder for an air-operated piston 20 which forces the opposite end 40 of the can against the knives or cutters of the apparatus.

The other part 22 of this form of housing contains a novel plunger device 24 which supports 45 the cut-out perforated end of the can while the piston 20 forces the can body over it to discharge the oil. The two parts of the housing are detachably connected by any suitable means, such as a series of lugs 26 on one of the parts which 50 are movable in bayonet-type recesses on the other part.

The piston 20 consists of two parts clamping 55 a suitable piston packing 28 between them. It may be provided, for example at its center, with

a relief valve 30 shown as consisting of two connected members on opposite sides of the piston, one of these members being a disk which is pushed back into seated position, to seal the port through the piston, by placing of the can of oil in the housing. The piston carries a bumper spring 32, the end convolution of which is shown attached to the piston by means such as an attaching stamping 34.

10 The end of part 18 of the housing is shown as a die-cast element 36 threaded to the end of the cylindrical portion of the housing part, and which is formed with means such as a threaded socket 38 for the attachment of an air hose or 15 the like.

This element 36 is formed with an inlet air passage controlled by a valve member 40 urged toward closed or seated position by a spring 42 and opened by means such as a pivoted lever 44 20 arranged for convenient manual operation. When the valve 40 is seated, the space back of piston 20 is vented through a passage 46. It will be seen that the depression of lever 44 causes the can to be forced forward by the pressure of the 25 air behind the piston 20.

The novel stationary plunger 24 is hollow, to form an oil discharge passage 50 communicating with a suitable spout or curved conduit 52, shown as normally closed by a spring-held check valve 30 54. The plunger is supported by being threaded at one end into a diecast end element 56, to which the spout 52 may also be threadedly connected.

The other end of the plunger 24 has threaded 35 there-into a hollow shouldered fitting 58, the inlet in the end of which has associated therewith an outwardly-opening ball check valve 60, prevented from undue displacement by any suitable 40 means such as a retainer 62 held in place by a washer 64 clamped between the plunger 24 and the end of the fitting 58. The end of the fitting has rigidly mounted thereon a knife or cutter 66 shaped to punch out an outlet or discharge opening in the end of the can when the piston 20 45 pushes it forward.

The end of the fitting 58 is slidably embraced by a seal consisting of stampings 68 and 70, embracing between them at one end a packing 72 encircling the fitting 58 behind the shoulder 50 formed thereon, and formed to support at the other end a packing 74 engageable with the can end in a zone encircling the opening formed by the cutter 66.

A relatively heavy coil spring 76, held in compression 55 between the seal just described and a cup-shaped stamped retainer 78 seated against the end of the plunger 24, permits the seal to yield as the can is forced forward, during the operation (first) of the knife or cutter 66 and (second) while the end of the can is cut out from the can body by an annular knife or cutter 80 seated against, and suitably secured to, the stationary retainer 78.

The end of the can, as it is forced forward to 65 cut out the end in this manner, engages the end edge of an annular member 82 backed up by a spring 84 (which may be considerably lighter than the spring 76). The spring 84 is shown 70 confined between the member 82 and the diecast end 56, which is shown formed with an annular recess receiving the end of the spring. Member 82 is formed with an annular shoulder which initially seats against an out-turned end flange 75 on the stationary retainer 78, so that the latter

serves as a stop against which the element 82 is urged by its spring 84.

The knife 80 may be arranged to start cutting before knife 66 has finished its operation, as the latter continues its operation until the end of the can is entirely severed from the can body. During this cutting operation, the seal 68-74 yields against the resistance of the spring 76. As soon as the can end is cut free, the spring 76 pushes it forward until the pressure of the spring 10 on the seal balances the pressure on the oil in the can from piston 20.

After the end of the can is formed with an outlet opening by the cutter 66, and after the end is cut out by the cutter 80, further advance 15 of the piston 20 forces the can over the cut-out can end, to force the oil out through the passage 50 and out through the discharge conduit 52. The end of the piston stroke is determined by engagement of the annular element 82 with 20 a stop shoulder 90 formed on the diecast end 56. When the piston 20 stops in the position so determined, which is before either of the cutters 66 or 80 engages the bottom of the can, the spring 76 forces the cut-out can end clear down to the 25 bottom of the can, thus completing the discharge of the oil without in any way damaging the can body.

The embodiments of Figures 3 and 4 differ 30 from that of Figure 1 principally in that the can body is held stationary, while the cut-out can end is moved to the bottom of the stationary can body to discharge the contents. The embodiment of Figure 3 differs from that of Figure 4 35 principally in that the apparatus is provided with a "booster" piston of larger diameter for operating the cutters, this being desirable when high-pressure air is not available. Where the parts in Figures 3 and 4 are the same as in Figure 1, the same reference characters are used; where the 40 parts are not the same, but have the same or analogous functions, the reference characters are increased by 100 in Figure 3 and by 200 in Figure 4.

Figure 3 shows a low-pressure "gun" having 45 the can held stationary in a two-part housing 118-122 (shown with the bayonet connections 26). The knives or cutters 66 and 180 are mounted on the end of a movable tubular plunger 124 connected to the air-operated piston 128 for 50 movement against the resistance of a pair of coaxial coil return springs 184. The plunger 124 telescopes on a stationary tube 125 to form the oil passage 50 leading to the outlet conduit 52. The end 156 is shown formed with an annular 55 stop 157 which determines the released position of the piston 120.

The lower portion of the casing has three sections connecting the casing portions 122 and 156. One of these is a die-casting 123, into the end 60 of which the casing portion 122 is shown threaded, and which is formed with a sleeve portion 127, provided with a leather sealing packing 129, encircling and guidingly supporting the plunger 124, and providing an air seal for the operation 65 of the booster piston as described below.

The two other sections are coaxial tubes 131 and 133, of different diameters, both threaded into the section 123 and the outer one threaded into the end section 156, leaving between them 70 an annular air passage 135 leading to the pressure face of the piston 120. The inner tube 131 forms a cylinder for the piston 120. The springs 184 are arranged coaxially within these tubes and coaxially about the plunger 124.

In this apparatus, a large-diameter "booster" piston 159 of limited stroke is slidably sleeved on the plunger 124, and on forward movement engages the retainer 178, and carries the plunger 124 forward far enough to operate the cutters 66 and 180 whereupon the piston 159 comes to rest against a stop formed by inwardly flanging the end of the casing section 122. The piston 159 has a leather seal 161 encircling the plunger 124, and through which the plunger 124 slides after the piston 159 stops.

The casing section 123 is formed to provide an air cylinder 163 for the piston 159 and this, as well as the passage 135, communicates with an air inlet passage 165 leading from the inlet port 138 and controlled by the valve 140 the head of which is engaged by an operating pin on the lever 144.

The stroke of piston 120 is determined by engagement of the piston with a stationary stop sleeve 190.

In this apparatus a safety device is provided to prevent the air valve 140 from being opened when the casing sections 118 and 122 are separated. In the arrangement illustrated, a plunger or lengthwise-movable pawl 192 is urged downwardly (in the drawings) by means such as a spring 194, and has at its upper end a pin 196 or the like which is brought by downward movement of the pawl into the path of a stop finger 198 on the upper end of the lever 144, to prevent the operation of the lever to open the air valve. The lower end of the pawl 192 is bent over to ride in a slot 200 in the casing section 122, in the path of a cam surface 201 formed on the casing section 118, so that the insertion and turning of the latter to secure it to the section 122 forces the pawl upwardly to release the air valve. If desired, the pawl-engaging surface could be provided on the can instead of on the casing section 118.

In the operation of this embodiment, after the closing of the casing 118-122 releases the air valve, operation of the lever 144 supplies air to the cylinder 163 as well as to the passage 135. The operation is in the following sequence: (1) the pistons 159 and 120 operate the cutter 66 to form a discharge outlet opening in the can and at the same time to seat the seal 68-74 against the can end; (2) both pistons 159 and 120 operate the annular cutter 180 to cut out the can end; and (3) the piston 120 moves the can end to the bottom of the can to discharge the contents.

Parts in Figure 4 which are not exactly the same as, but which are analogous to, parts shown in Figure 3, are indicated by the same reference characters increased by 100. It is believed that the operation will be apparent from the foregoing description of Figures 1 and 3.

It should be noted, however, that there is no "booster" piston in this embodiment, and piston 220 does all the work of operating the two knives 66 and 280, until a stop boss 290 formed on the piston engages the stationary flange 227. There are two coaxial springs 276 acting on the seal in this embodiment, to increase the pressure on the seal.

The safety pawl 292 is pulled downward, against the resistance of its spring 294, to move pin 296 out of the path of part 298 of lever 244, by an inclined cam slot 219 in casing section 218 which receives a cam pin on the end of the pawl 292 and forces it downwardly as the bayonet lugs 26 are locked by turning the casing section

218. The air passage 235 is formed by a small conduit, instead of being the space between coaxial tubes.

While three illustrative embodiments of my invention have been described in detail, it is not my intention to limit the scope of the invention to those particular embodiments or otherwise than by the terms of the appended claims.

I claim:

1. A dispenser comprising an original package 10 of substantially cylindrical side wall shape and having a closed end adapted to be substantially wholly cut away, and means for cutting away said closed end and for forcing material through an opening in said closed end, comprising an annular knife engageable with said closed end adjacent said side wall to cut out said end and a cutter within the outline of said knife adapted to make an opening in said end, means for relatively moving the package and said knife and 20 cutter to form an opening in said end and then cut it away from the side wall, and means for moving said cut end and said package relatively to each other to force the material from the package through said opening.

2. A dispenser comprising an original package 30 of substantially cylindrical side wall shape and having a closed end adapted to be substantially wholly cut away, and means for cutting away said closed end and for forcing material from said package comprising an annular knife engageable with said closed end adjacent said side wall to cut out said end and a cutter adapted to make an opening in said package, power operated means for relatively moving the package and said 35 knife and cutter to form an opening in said end and then cut it away from the side wall, and power-operated means for moving said cut end and said package relatively to each other to force the material from the package through said 40 opening.

3. A dispenser comprising an original package 45 of substantially cylindrical side wall shape and having a closed end adapted to be substantially wholly cut away, and means for cutting away said closed end and for forcing material through an opening in said closed end comprising an annular knife engageable with said closed end adjacent said side wall to cut out said end and a cutter within the outline of said knife adapted to make an opening in said end, power-operated means for relatively moving the package and said 50 knife and cutter to form an opening in said end and then cut it away from the side wall, and means for moving said cut end and said package relatively to each other to force the material from the package through said 55 opening.

4. Dispensing apparatus having means for forming a discharge outlet in one end of a can, a substantially ring-shaped knife for cutting out the end formed with the discharge outlet, and means for relatively moving the can and said end for effecting the discharge of the can's contents through said outlet.

5. Dispensing apparatus having means for forming a discharge outlet in one end of a can, a substantially ring-shaped knife for cutting out one end of the can, fluid pressure means for moving the knife and the can relatively whereby the knife cuts out the can end, and means for relatively moving the can and said cut-out end for effecting the discharge of the can's contents through said outlet.

6. Dispensing apparatus having power-operated means for forming a discharge outlet in 75

- one end of a can, a substantially ringshaped knife for cutting out one end of the can, fluid pressure means for moving the knife and the can relatively whereby the knife cuts out the can end, and means for relatively moving the can and said cut-out end for effecting the discharge of the can's contents through said outlet.
7. Dispensing apparatus comprising a device having a space to receive the end of a can, means for holding a can with its end in said space, an annular knife and a cutter within the outline of the knife to act on said end of the can to form a discharge opening in and to cut out said end of the can, and means for effecting relative movement of the can and said cut-out end to discharge the contents of the can through said opening.
8. Dispensing apparatus comprising a device having a space to receive the end of a can, means for holding a can with its end in said space, a cutter arranged to form a discharge opening in the can, an annular knife arranged to act on one end of the can to cut out said end of the can, fluid pressure means for moving the knife and the can relatively whereby the knife cuts out the can end, and means for effecting relative movement of the can and said cut-out end to discharge the contents of the can through said opening.
- 30 9. Dispensing apparatus comprising a device having a space to receive the end of a can, means for holding a can with its end in said space, a power-operated cutter arranged to form a discharge opening in the can, an annular knife arranged to act on one end of the can to cut out said end of the can, fluid pressure means for moving the knife and the can relatively whereby the knife cuts out the can end, and means for effecting relative movement of the can and said cut-out end to discharge the contents of the can through said opening.
- 45 10. Dispensing apparatus comprising, in combination with a can having one end faced internally with a packing member having a central opening, a device receiving said end of the can, means for holding the can and said device together, means for forming a discharge opening through said end within the outline of the opening in the packing member, means for cutting said end free from the can, and means for relatively moving the can and the cut-out end with its packing member, to force the contents of the can out through the discharge opening.
- 55 11. Dispensing apparatus comprising, in combination with a can having one end faced internally with a packing member having a central opening, a device receiving said end of the can, means for holding the can and said device together, means for forming a discharge opening through said end within the outline of the opening in the packing member, and power-operated means for cutting said end free from the can and for then relatively moving the can and the cut-out end with its packing member, to force the contents of the can out through the discharge opening.
- 60 12. The process of dispensing material from a can filled therewith and sealed with a packing member internally facing one of its ends and formed with a central opening, which comprises puncturing a discharge opening through said end of the can within the outline of said central opening in the packing member, cutting said end free from the can, and relatively moving the can and the cut-out end with its packing

member to force the material from the can through the discharge opening.

13. Dispensing apparatus comprising a device associated with the end of a can and having a blade for puncturing said end of the can and an annular seal engageable with said end surrounding said blade and having an annular cutter to cut out said end of the can outside of said seal, whereby the cut-out end may be forced through the can to dispense the contents thereof through the punctured portion.

14. Dispensing apparatus comprising a device associated with the end of a can and having a blade for puncturing said end of the can and an annular seal engageable with said end surrounding said blade and having an annular cutter to cut out said end of the can outside of said seal, and power-operated means for relatively moving the can and said device with the cut-out end to dispense material from the can through the punctured end.

15. Dispensing apparatus comprising a circular knife for severing one end of a can from the can body, a cutter for forming a discharge opening in said end of the can, a plunger supporting the knife and cutter and having an annular seal for engaging the cut-out end around the discharge opening and having a discharge passage communicating with the discharge opening within said seal, a support engaging the can, and means for relatively moving the support and the plunger to dispense material from said can.

16. Dispensing apparatus comprising a circular knife for severing one end of a can from the can body, a cutter for forming a discharge opening in said can, a plunger supporting the knife and having a part engaging the cut-out end, an annular seal for engaging the can around the discharge opening, a part having a discharge passage communicating with the discharge opening within said seal, a support engaging the can, and power-operated parts for relatively moving the support and the plunger to dispense material from said can.

17. Dispensing apparatus comprising a circular knife for severing one end of a can from the can body, a cutter for forming a discharge opening in said end of the can, a plunger supporting the knife and cutter and having an annular seal for engaging the cut-out end around the discharge opening and having a discharge passage communicating with the discharge opening within said seal, a support engaging the can, and a fluid actuated piston for relatively moving the support and the plunger to dispense material from said can.

18. Dispensing apparatus comprising means to cut out one end of a can adjacent the can wall, and to form a discharge opening in said end, a plunger having means for supporting the cut-out end against movement, and having a discharge passage communicating with said opening, and means for moving the can body over the cut-out end while so supported, to discharge the contents of the can through said opening.

19. Dispensing apparatus comprising means to cut out one end of a can adjacent the can wall, means to form a discharge opening in said can, a plunger having means for supporting the cut-out end, a discharge conduit communicating with said opening, and means for moving the can body over the cut-out end while supported by said plunger, to discharge the contents of the can through said conduit.

20. A dispenser of the class described compris-

- ing a tubular plunger having a discharge conduit communicating with its interior space and having at its end an annular seal engageable with one end of a can, a cutter mounted on said plunger 5 within the outline of said seal and adapted to puncture said end of the can, an annular knife carried by said plunger and arranged to cut said end of the can free from the can body after it is punctured by said cutter, and means for relatively moving the can body and the plunger to dispense the contents of the can through the conduit.
21. A dispenser of the class described comprising a tubular plunger having a discharge conduit 15 telescoping said plunger and communicating with its interior space and having at its end an annular seal engageable with one end of a can, a cutter mounted on said plunger within the outline of said seal and adapted to puncture said end of the can, an annular knife carried by said plunger and arranged to cut said end of the can free from the can body after it is punctured by said cutter, and means for moving said plunger into the can 20 in telescoping relation to said conduit, to dispense the contents of the can through said conduit.
22. A dispenser of the class described comprising a stationary tubular plunger having a discharge conduit connected thereto and having its 25 end engageable with one end of a can, a cutter adapted to puncture one end of the can, a seal engaging the can around said cutter, an annular knife arranged to cut the end of the can engaged by the plunger free from the can body after the can is punctured by said cutter, and means for moving the can body over the plunger to dispense the contents of the can through the conduit.
23. A dispenser of the class described comprising 30 a tubular plunger having a discharge conduit communicating with its interior space and having at its end an annular seal engageable with one end of a can, a cutter mounted on said plunger within the outline of said seal and adapted to puncture said end of the can, an annular knife carried by said plunger and arranged to cut said end of the can free from the can body after it is punctured by said cutter, and means for relatively moving the can body and the plunger to dispense 35 the contents of the can through the conduit, together with a spring interposed between the seal and a part carried by said plunger, the seal being yieldable relatively to the plunger against the resistance of the spring while the cutter and the knife are operated on the can as described.
24. A dispenser of the class described comprising 40 a tubular plunger having a discharge conduit telescoping said plunger and communicating with its interior space and having at its end an annular seal engageable with one end of a can, a cutter mounted on said plunger within the outline of said seal and adapted to puncture said end of the can, an annular knife carried by said plunger and arranged to cut said end of the can free from the can body after it is punctured by said cutter, and means for relatively moving the can body and the plunger to dispense 45 the contents of the can through the conduit, together with a stop preventing engagement of the cutter and the knife with the opposite end of the can.
25. A dispenser of the class described comprising 50 a stationary tubular plunger having a discharge conduit connected thereto and having its end engageable with one end of a can, a cutter adapted to puncture one end of the can, a seal engaging the can around said cutter, an annular knife arranged to cut the end of the can engaged by the plunger free from the can body after the can is punctured by said cutter, and means for moving the can body over the plunger to dispense 55 the contents of the can through the conduit, together with a spring interposed between the seal and a part carried by said plunger, the seal being yieldable relatively to the plunger against the resistance of the spring while the cutter and the knife are operating on the can as described.
26. A dispensing apparatus comprising air-operated means for cutting out one end of a can and forcing it through the can body to dispense 60 the contents of the can, means for supporting a can for the operation thereon of said air-operated means, a valve having a manually-operated control member and controlling the supply of air to the air-operated means, and an interlock preventing operation of the control member unless a can is in position supported by the supporting means.
27. A dispensing apparatus comprising air-operated means for cutting out one end of a can and forcing it through the can body to dispense 65 the contents of the can, means for supporting a can for the operation thereon of said air-operated means, a valve having a manually-operated control member and controlling the supply of air to the air-operated means, and an interlock preventing operation of the control member and which is moved out of the way by the can-supporting means.
28. A dispenser of the class described comprising 70 a tubular plunger having a discharge conduit communicating with its interior space and having at its end an annular seal engageable with one end of a can, a cutter mounted on said plunger within the outline of said seal and adapted to puncture said end of the can, an annular knife carried by said plunger and arranged to cut said end of the can free from the can body after it is punctured by said cutter, and means for relatively moving the can body and the plunger to dispense the contents of the can through the conduit, together with a stop preventing engagement of the cutter and the knife with the opposite end of the can.
29. That method of dispensing the contents of 75 a can which comprises forming an opening in one end of the can, cutting one end of the can free from the can body, supporting a discharge means in sealed relation to the end of the can around said opening, supporting the cut-out end of the can against movement, and moving the can body forcibly over said supported cutout end to force 80 its contents through the discharge means.
30. That method of dispensing the contents of 85 a can which comprises forming an opening in one end of the can, cutting said end of the can free from the can body, supporting a discharge means in sealed relation to said end of the can around said opening, supporting said cutout end of the can against movement, and moving the can body forcibly over said supported cutout end to force 90 its contents through the discharge means.
